UNITED STATES PATENT OFFICE

DOMINGO OXARART, OF LOS ANGELES, CALIFORNIA.

VENDING MACHINE.

Application December 23, 1925. Serial No. 77,215.

My invention is a vending machine of the coin operated type, designed particularly to vend loose articles such as nuts, loose candies, etc.

5 An object of my invention is a vending machine having a coin control in which the vending device is mounted on a shaft and the movement of the shaft is controlled by a coin receiving device, the coin operating a latch to allow rotation of the shaft and discharge or vending of the article.

A further object of my invention is a vending machine provided with a hopper over which a container having the articles to be vended may be inserted, preferably by inverting and the articles discharged through a chute at the side of the vending machine, the articles being fed from the hopper to the chute by a rotary shaft.

20 In my invention I utilize a cabinet in the form of a small size box which may be placed on a table or stand, this box having a longitudinal shaft, one portion of which has a transfer device for receiving and carrying the articles to be vended, this device being situated at the base of a hopper forming a closure therefor and discharging into a chute, the rotation of the shaft being controlled by a latch engaging in a coin receiving disc, the disc having a socket adapted to receive and hold a coin, whereby the coin acts as a cam and displaces the latch. The articles to be vended are preferably enclosed in a glass jar which may be inverted over the hopper, allowing the feeding of the articles to the hopper as they are vended.

25 My invention will be more readily understood from the following description and drawings, in which:

30 Figure 1 is a perspective view of my vending machine illustrating the external construction.

35 Fig. 2 is an elevation showing the interior mechanism with the side plate removed.

40 Fig. 3 is a vertical longitudinal section through the actuating shaft, the coin controlled mechanism and the vending portion of the machine.

45 Fig. 4 is a transverse section on the line 4—4 of Fig. 4, in the direction of the arrows, through the coin controlled mechanism.

50 Fig. 5 is a vertical transverse section on the line 5—5 of Fig. 3 in the direction of the arrows.

55 My vending machine considered generally comprises a box-like cabinet 1 having

a removable side wall 2 with a receiving cup 3 attached thereto, in which the articles to be vended are deposited. A container 4 preferably made of glass is inverted, having the neck of the container extending into an opening 5 in the top of the cabinet. A coin slot 6 leads to a coin controlled mechanism and a handle 7 operates a shaft for vending the articles after deposit of a coin in the coin slot, as will be hereafter described.

The vending mechanism is constructed substantially as follows, having reference particularly to Figs. 2, 3 and 5.

The neck 8 of the container is inserted part way in the hopper 9 formed by the converging side walls 10 and the parallel end walls 11. These end walls have a semi-circular cut out section 12 adapted to fit the transfer block 13 mounted on the rotatable shaft 14. The transfer block has an elongated groove 15, the cubic capacity of such groove being that of the material to be vended corresponding to the value of a coin utilized to actuate the vending machine. A chute 16 is positioned below the transfer block and has a discharge end through an aperture 17 in the removable side 2 leading to the cup 3.

The shaft 14 is supported in journals 18 and 19 at opposite ends of the cabinet and one end extends through an aperture 20 in one of the end walls and has the handle 7 attached thereto, the handle being for the purpose of rotating the shaft. A counter-weight arm 21 is rigidly attached to the shaft and carries a counter-weight 22 at its lower end, this weight being sufficient to hold the shaft with the groove 15 in an uppermost position and the coin controlled mechanism in its normal stationary position as hereafter described.

A rubber bumper 23 is attached to the base of the cabinet and a rubber bumper 24 is attached to one of the end walls 11 of the hopper, these being designed to form a stop for the counter-weight arm.

The coin controlled mechanism is substantially as described, having reference particularly to Figs. 2, 3 and 4. The coin slot 6 is of the conventional type and proportioned to the size of coins intended to be used in the vending machine. A coin receiving disc 25 is rigidly attached to the shaft 14 and is shaped in profile somewhat as a cam, having a portion 26 having a coin

5 pocket 27 of greater radius than the portion 28, thereby forming a radial surface 29 between these portions of the coin disc. This surface forms an abutment for catching on the latch 30 which is hinged by a spring hinge 31, to the frame 32. The spring hinge normally forces the latch into engagement with the coin disc. The latch has a notch 33 formed in the hook end 34 to allow the 10 coin to pass through as hereafter described. A coin box 35 is located in the base of the cabinet to receive the coin.

15 The operation of my coin controlled vending machine is substantially as follows:

15 When a coin is inserted in the coin slot 6 it falls by gravity into the coin pocket 27 as this pocket is normally retained in the uppermost position by means of the counter-weight 22, this position being shown in Fig. 4. However, should the shaft and coin disc 20 25 be partially rotated by the handle 7, it can only be rocked part way forward or in an anti-clockwise direction as indicated by Fig. 4, until the abutment 29 engages the 25 hook 34 of the latch 30. The counter-weight arm 21 engaging the bumper 23 prevents rotation in the other direction. A person 30 therefore finding the device inoperative would allow it to come to its normal position for receiving the coin in the coin pocket. As the purchaser rocks the handle 7 in a 35 clockwise direction as indicated in Fig. 1, the coin disc is rotated in an anti-clockwise direction as indicated in Fig. 4, the coin passing through a groove 36 in the base of the coin slot and thereby engaging the latch 30 and pressing it outwardly at substantially the same time or slightly before the hook 34 engages the abutment 29. This 40 forces the latch outwardly a sufficient distance for it to clear the abutment 29 and to allow rotation of the shaft until the counter-weight arm strikes the bumper 24. In this 45 action the coin passes through the notch 33 in the latch and is deposited in the coin box 35.

The vending action is as follows:

50 When the shaft 14 is rotated as above described, it will be understood that the hopper 9 is maintained full of the articles to be vended, such articles being peanuts, loose candy or other articles to be sold in bulk as distinguished from package sale. Therefore the groove 15 is filled with the articles 55 to be vended and as the block 13 is rotated with the shaft, this pocket goes downwardly in an anti-clockwise direction as indicated in Fig. 5, below the lower edge of the hopper and drops the articles into the chute 16, from whence they pass through the aper-

ture 17 to the pocket 3 on the removable side of the cabinet. The purchaser may then take the articles from the cup. On releasing the handle 7 the counter-weight 22 will turn the shaft 14 with the coin disc and the 65 vending block to their normal positions as indicated in Figs. 3, 4 and 5.

It will be noted that the groove 15 with the material to be vended and its relation to the hopper 9 are such that the latch 30 must 70 ride off the portion 26 of the disc and pass the abutment so as to engage therewith on return motion before the groove can be filled with the articles from the hopper.

It will thus be seen that I have invented a 75 vending machine which is coin controlled, of a very simple character requiring comparatively few parts and that the device may be made to occupy comparatively small space compared with the bulk of the goods 80 to be vended.

My vending machine and coin controlled mechanism may be changed in general details and in specific features without departing from the spirit thereof as set forth in 85 the description, drawings and claims.

Having described my invention, what I claim is:

1. In a vending machine, a rock shaft, a disc mounted thereon having a coin pocket, 90 a radial abutment on said disc, a spring pressed latch having a hook end, the hook end being positioned to engage the said abutment on a slight rocking of the disc, there being a notch in the hook end, the latch 95 being engaged by a coin in the coin pocket on partial rotation of the disc, such coin pressing the latch and disengaging the hook end from the abutment, the coin falling through the notch allowing rotation of the 100 disc.

2. In a vending machine a box like structure having a coin chute with a lateral groove at the lower end on one side, a rock shaft having a disc, the disc being below 105 the chute and having a coin pocket therein, a radial abutment on the disc, a latch having a hook end with a notch in such end, a spring normally pressing the latch to engage the hook end with the abutment, the latch 110 being engaged by a coin in the coin pocket on partial rotation of the disc, such coin pressing the latch and disengaging the hook end from the abutment, the coin falling through the notch allowing rotation of the 115 disc.

In testimony whereof I have signed my name to this specification.

DOMINGO OXARART.
